CONTROL CIRCUITS

Henry V. Johnson, Springfield, Mass., assignor to
 Westinghouse Electric & Manufacturing Company, East Pittsburgh, Pa., a corporation of Pennsylvania

Application March 27, 1937, Serial No. 133,417

5 Claims. (Cl. 250—17)

My invention relates to the field of radio, and more particularly to a control circuit for use in connection with radio transmitters.

It is often desirable, from an economic viewpoint, to operate a plurality of transmitters from a common source of supply, and sometimes necessary to do this, where only one source of supply is available.

In systems of this character, where the power source constitutes a low voltage alternating current supply which is stepped up, rectified and filtered, the transmitters are connected in multiple to the high voltage direct-current side of the common supply source, which often has to deliver 15 plate voltages in the neighborhood of 15,000 volts and a load current up to 2 amperes per transmitter.

It is not always essential in the operation of the system, that all the transmitters be operating 20 at the same time, and very often it is necessary to disconnect one or more of the transmitters, either because it is not desired to utilize them at the time, or because of some transient or overload condition occurring in the circuits of one of 25 the transmitters.

In prior practice it was necessary in order to connect or disconnect one or more of the transmitters at will, or during the established interval of transient or overload conditions, to open the 30 power supply circuit on the low voltage alternating current side. After the entire system has been thus detached from its source of voltage, the particular transmitter desired to be removed from the circuit, was then disconnected and the source 35 of potential supply again applied in the usual manner. It will be apparent that this procedure necessitated suspension of service for an appreciable time, for those transmitters which were desired to be kept in operation and thus introduced 40 interruptions in the scheduled transmission.

Attempts have been made to solve the problem of permitting the individual transmitters to be switched out of circuit on the high voltage direct 45 current side, so that the operation of the remaining transmitters may not be disturbed, in the event of an overload condition or in the event when it was desired to remove one of the transmitters from the air. Such attempts, however, 50 have not been wholly satisfactory by reason of the difficulty involved in designing suitable switching apparatus for operation at such high direct-current voltages and such heavy loads. Arcing across the opening contacts constituted a 55 most troublesome factor.

It is an object of my invention to provide a system for enabling one to disconnect a transmitter on its high voltage direct-current supply source without noticeably effecting the operation of other transmitters connected to the same supply source. 5

A further object of my invention is to enable the switching of a transmitter on the high voltage direct current end of its supply source without introducing arcing difficulties across the switching contacts. 10

A further object of my invention resides in the provision of a control system which shall automatically disconnect a transmitter upon the establishment of an overload condition, without necessitating any noticeable interruption of the operation of other transmitters which derive their potential from the same supply source. 15

Additional objects of my invention will be brought out in the following description of the 20 same when taken in connection with the accompanying drawing, wherein the single figure constitutes a schematic diagram of a potential supply source feeding a plurality of transmitters in multiple, and a control circuit for accomplishing the objects of my invention. 25

The transmitting system constitutes a plurality of individual transmitters 1, 2 and 3 respectively connected in multiple to the high voltage direct current end of a power supply circuit which in 30 the example shown, constitutes a three-phase alternating current, low voltage supply 7 which is stepped up, rectified and filtered to obtain the high voltage direct-current plate potential for the transmitters. Each of the circuits to the 35 transmitter contains a pair of normally closed contacts 9 and an overload relay coil 10 in series with the transmitter.

The pair of closed contacts 9 in the line to its respective transmitter is associated with a relay 11 40 which is provided with four pairs of contacts 9, 13, 15 and 17. Two pairs of these contacts 9 and 17 including the pair in the circuit to the transmitter are normally closed during operation of the transmitters, whereas the remaining two pairs 13 and 45 15 normally remain open.

The overload relay 10 in each of the transmitter branch circuits is provided with two pairs of contacts 19 and 21, one pair 19 of which is normally closed and the other pair 21 being normally 50 open.

In addition to the relays identified above, the control system utilizes an additional relay 23 having four pairs of contacts, three of which designated by reference numeral 25 are located in the 55

3 phase lines to the rectifier, and during the application of plate excitation to any of the transmitters, these three pairs of contacts are normally in closed position. The fourth pair of contacts 5 27 of the relay are open when the other three pairs are closed and vice-versa.

The arrangement and interconnection of these relays and contacts are such that the relay winding 23 of the main alternating current contacts 10 25 is connected from a source of excitation in series with the normally closed contacts 19 of the overload relays 10 and normally closed contacts 41 of switch 40. The contactor windings 11 are all connected in parallel circuits, each parallel branch comprising the coil 11, a pair of normally closed associated contacts 17 and the normally open contacts 21 associated with the overload relay 10. The normally open contacts 27 of the main alternating current relay winding 20 23, are common to all the branch circuits, and complete the circuit across the source of excitation.

Across each of the normally closed contacts 19 of each of the overload relays 10 is connected a 25 pair of normally open contacts 13 associated with the corresponding contactor winding 11 and normally closed contacts 41 of switch 40.

Across each of the normally open contacts 21 of each of the overload relay 10 is connected a 30 pair of normally open contacts 42 associated with the corresponding switch 40.

The normally open contacts 15 associated with each of the contact windings 11 are connected in series with their associated winding across the 35 control source of potential through a manually controlled but normally closed circuit opening device 20.

The cooperation and sequence of operation existing among the various elements of the control circuit just described, may best be brought out by assuming an overload condition to occur in one of the transmitters; for example transmitter No. 1. Upon the occurrence of such a condition, the overload relay 10 in series with 40 that transmitter will become excited to the extent of opening its normally closed contacts 19 and closing its normally open contacts 21 and locking itself in this condition. Opening of the normally closed contacts 19 interrupts the series 45 circuit through the normally closed contacts 19 of the other overload windings 10, normally closed contacts 41 of the switches 40, and the winding 23 of the main alternating current breaker. This main breaker winding thereby becomes de- 50 energized and opens the main breaker contacts 25 thus interrupting the source of supply to the rectifier. The breaking of the circuit through the opening of these contacts is immediately followed by the closing of the normally open contacts 27 associated with the same winding. This 55 completes a circuit through the contactor winding 11 through the normally open contacts of the overload relay 21, which normally open contacts have previously been closed due to the operation of the overload relay. The excitation circuit to the contactor winding 11 also includes a pair of its normally closed contacts 17. Upon excitation, this relay opens its normally closed contacts 9 and 17 and closes its normally open contacts 13 and 15, one immediate result of which is to disconnect the transmitter No. 1 from the source of supply on the high voltage side, through the opening of the normally closed contacts 9 in series with the transmitter. The second pair 60 70 of normally closed contacts 17 which have now

been opened, break the excitation circuit to the winding 11, which circuit included the contacts 21 of the main breaker coil 23, but the excitation is not lost as the coil 11 has been connected directly across the control supply source through the closing of a pair of its normally open contacts 15. This acts as a locking circuit to maintain this relay winding in a state of continuous excitation to thereby maintain the troublesome transmitter disconnected from the circuit. The 10 excitation of the relay winding 11 at this point has also become independent of the normally open contacts 27 of the main breaker.

Since the normally closed contacts of the overload relay are now locked in open position, they 15 serve to maintain the circuit through the main breaker winding 23 open and thereby prevent its excitation, it is essential to provide some means for permitting the main breaker winding to receive excitation to reclose the contacts 25 which 20 connect the alternating current source to the rectifier. This comprises the purpose of the remaining normally open contacts 13 of the container relay 11, which normally open contacts are connected in shunt to the normally closed 25 contacts 19 of the corresponding overload relay 10. The normally open contacts 13 at this stage of operation of the control circuit are now in closed condition due to the permanent excitation of its associated relay winding 11, and it, therefore serves to replace the normally closed contacts 19 of the corresponding overload relay 10 which contacts are now in open condition. Thus, the main breaker winding again becomes energized and recloses the circuit to the rectifier to 30 provide and supply the high voltage on the direct-current side to the remaining transmitters.

Should it be desired to disconnect a transmitter from the D. C. power source this may be accomplished by operating switch 40, associated 40 with this transmitter, such that its normally closed contacts 41 open and its normally open contacts 42 close. The sequence of operation is exactly the same as when overload relay 10 operated except normally closed contacts 41 of 45 the switch 40 are substituted for normally closed contacts 19 of overload relay 10 and the normally open contacts 42 of switch 40 are substituted for normally open contacts 21 of overload relay 10.

The sequence of operation of the components 50 of the control circuit as just described occurs so quickly, that a transmitter may be disconnected from the circuit and the remaining transmitter replaced in operation within an exceedingly short period of time of the order of one-eighth of a second. Insofar as this effects the 55 operation of the remaining transmitters, their operation from all practical purposes has been essentially uninterrupted and in fact the transmitters are effectively maintained in operation 60 during the switching process.

By reason of the fact that the system is first opened on its low voltage alternating current side, the disconnecting of any one of the individual transmitters on the high voltage direct current 65 side during the brief period of interruption of the alternating current supply, occurs without any sign or tendency to arc at the contacts where the opening of the circuit on the high voltage side occurs, namely at the contacts 9 located in the 70 circuit to the transmitter.

As a precaution against the possibility of extreme overload conditions injuring the overload relays 10, a resistor 31 is connected in series therewith and another resistor 33 in parallel.

In order to replace a transmitter on the air, which has previously been removed due to an overload condition, it is only necessary to reset the overload relay 10 associated with that transmitter and open the locking circuit of the corresponding contactor relay 11 by operating the manual circuit opening device 29 in its holding circuit. Where the disconnection of the transmitter is brought about manually through the operation of a switch 40, a procedure similar to the above is followed in resetting the circuit, except in that the switch 40 is restored to its initial condition instead of the relay 10, prior to opening the locking circuit of the corresponding contactor relay 11.

These two simple operations reset this portion of the control circuit to its normal condition, permitting the contacts 9 in the line to the transmitter to close and thereby provide for the application of high voltage direct current excitation to the transmitter in question.

While I have disclosed my invention in great detail, it is apparent that the embodiment described is susceptible to many modifications without departing from the scope of my invention, and I therefore, do not desire to be limited in my protection to the specific details disclosed, except as may be necessitated by the prior art and the appended claims.

30 I claim as my invention:

1. In combination, a low voltage alternating current supply source, a plurality of transmitters connected in multiple and utilizing high direct current voltages for operation, means for converting said alternating current supply source into direct current of relatively high voltage suitable for energization of said transmitters, switching means for connecting said direct current to each of said transmitters and means for interrupting 40 and then restoring said supply of alternating current within an inappreciable time interval, and means for automatically disconnecting said high direct current voltage from any of said transmitters to be deenergized, within the aforementioned period, while maintaining the high voltage connection to the other of said transmitters undisturbed.

2. In combination, a low voltage alternating current supply source, a plurality of transmitters forming a load circuit connected in multiple and utilizing high direct current voltages for operation, means for converting said alternating current supply source into direct current of relatively high voltage suitable for energization of 50 said transmitters, switching means for applying said direct current voltage thereto, and means operable upon overload conditions in any of said transmitters for interrupting the supply of alternating current voltage deenergizing thereby 55 said load circuit for an inappreciable period of

time of the order of a fraction of a second and means for disconnecting said transmitter, to be deenergized, within said inappreciable period, from said direct current supply, while maintaining the connection to the other of said transmitters undisturbed.

3. In combination a plurality of transmitters, a low voltage alternating current supply source, means for transforming said low voltage alternating current source into a high voltage direct current source, means for connecting said transmitters in multiple to said high voltage direct current source, and means responsive to an abnormal condition in one of said transmitters for momentarily interrupting the alternating current supply source thereby deenergizing all said transmitters and disconnecting one of said transmitters from the high voltage direct current source during said momentary interruption, said means for disconnecting being so arranged as to 20 be effective only for said abnormally operating transmitter and ineffective for the other of said transmitters.

4. In combination, a plurality of load circuits energized from a high voltage supply source, said source being obtained upon transformation of low voltage alternating-current supply energy, switching means operable to connect each of said load circuits to said high voltage source, means for disconnecting any of said load circuits at will from 30 said source comprising electromagnetic actuating means including switching mechanisms for disrupting said low voltage supply prior to disconnection of one of said load circuits from said high voltage supply source, and means automatically operable for reestablishing contact of 35 said switching mechanism upon effective disconnection of one of said load circuits while the connection of the other of said load circuits to said high voltage source remains undisturbed. 40

5. In combination, a plurality of load circuits energized from a high voltage supply source, said source being obtained upon transformation of low voltage alternating-current supply energy, individual switching means for said load circuits 45 operable to connect each of said load circuits in parallel to said high voltage source, means automatically operable upon overload conditions in any of said load circuits for disconnecting said circuits, without affecting the connection of the 50 other of said load circuits, comprising electromagnetic actuating means including switching mechanisms for disrupting said low voltage supply prior to disconnection of said load circuit from said high voltage supply source, and means 55 automatically operable for reestablishing contact of said switching mechanism upon effective disconnection of any one of said load circuits.

HENRY V. JOHNSON. 60
